卷之三

Henry Sorenson
INVENTOR

UNITED STATES PATENT OFFICE.

HENRY SORENSEN, OF SAN FRANCISCO, CALIFORNIA.

CONSTRUCTION OF FIREPROOF BUILDINGS.

Original application filed December 7, 1925, Serial No. 73,717. Divided and this application filed April 10, 1926. Serial No. 101,223.

While my invention may be utilized in various ways, I have, in the accompanying drawings, illustrated my invention applied to the construction of fireproof buildings.

5 In the said drawings:—

Fig. 1 illustrates a plan view of my invention, applied to floors, before the concrete is poured, but with the concrete in section shown in the lower walls on both sides, 10 and in the beam under the middle of the floor.

Fig. 2 is a cross section of Fig. 1 at *a—a*, after the concrete is poured and after the frames are removed.

15 Fig. 3 is a longitudinal section of Fig. 1 at *b—b*, after the concrete is poured and after the frames are removed.

Figures 4, 5, and 6 are enlarged fragments 20 of parts illustrating my invention.

Fig. 7 illustrates the enlarged fragment 25 of a reinforcement rod.

In the drawings, where similar numerals indicate similar parts, numerals 1 designate the forms for the concrete. Numerals 2 designate main angular wedge shaped pairs of 30 steel bands, which, together with their intervening concrete filling 16, form the main angular wedgeshaped supports which carry the floors. Numerals 3 designate lateral 35 wedgeshaped pairs of steel bands, which, together with their intervening concrete filling 16, form the lateral angular wedge-shaped supports which carry the floors. Numerals 4 designate the horizontal flanges

40 connected with bands 2 and with bands 3. Numerals 5 designate holes in bands 2. Belts 6 pass through holes 5. Beam 8 is supported by columns, not shown. Walls 7 and beam 8 serve as supports for the main

45 pairs of band 2. Main bands 2 support, in turn, the lateral pairs of angular wedge-shaped bands 3. I place band reinforcements 15 between the pairs of main bands 2, or between the pairs of lateral bands 3, or

50 between both. Numerals 10 designate the concrete. Flanges 4 are formed by a sharp bend along the edges of bands 2 and bands 3, and form an acute angle, i. e. an angle which is less than 90°.

55 Fig. 1 is a plan view of my invention before the concrete is poured. Numerals 1 designate the forms for concrete walls 7 and beam

8, besides the flat surface upon which the concrete floor is cast. The flat surface 1 is flush with the top of beam 8. I place the 55

pairs of bands 2, and the pairs of bands 3, upon their respective flanges 4, on the surface of forms 1. Due to the fact that the flanges form acute angles, the sides of bands 2, and bands 3, are sloping, and I place these 60 pairs of bands 2 and 3 with their sloping sides upward towards a point. I leave the individual bands, of the pairs of bands 2, and the individual bands, of the pairs of bands 3, at a suitable distance apart, forming 65

openings 11, for the reasons which I will show hereinafter. The shape of the main pairs of bands 2, and the shape of the lateral pairs of bands 3, are identical, but I give the ends of bands 3 a slope, which 70 corresponds to the slopes of the sides of bands 2. I place the pairs of bands 3 crossways, in their relation to the pairs of bands 2, so that bands 3 reach from the slope 75

of the sides of one pair of bands 2 to the slope of the sides of the other pair of bands 2, and the sloping ends of bands 3 will then rest upon the sloping sides of bands 2. As I have stated above the main pairs of bands 2 are supported by walls 7 and beam 8, and, 80 due to the sloping ends of bands 3, which rest on the sloping sides of bands 2, the pairs of main bands 2 will, in turn, support the lateral pairs of bands 3. Said main bands 2 are, preferably, made of heavier material 85 than the lateral bands 3.

In this way the pairs of main bands 2, together with the pairs of lateral bands 3, form rectangular wedgeshaped seats 9 in which concrete 10 rests. Concrete 10 is 90 wedged between the rectangular seats 9 and can get nowhere. By means of bolts 6, through holes 5, I interlock bands 2 and anchor said bands 2 to walls 7 and to beam 8, as shown at 12 and 13 on Fig. 1. By placing the pairs of bands 2 and 3, either closer or further apart, I decrease, or increase, the carrying capacity of the floors.

I strengthen walls 7 against the tension, caused by main bands 2, by placing pairs of bands 2 vertically in walls 7, as shown 100 in Fig. 1. These vertical pairs of bands 2 reach from floor to floor, and are placed with their flanges 4 resting against the sides

of the concrete floors. The tension, caused by the main floor bands 2, in walls 7, is thereby counteracted by the resistance derived from the whole area of the concrete 5 floors themselves.

Fig. 7 is an enlarged fragment of a section of the reinforcements 15 resting on one of the sloping sides of the pairs of bands 3, to which I have referred above. Said reinforcements 15 may be of any known shape, but I prefer to give reinforcements 15 sloping ends, as shown, so that the sloping ends of 15 may fit against the sloping sides of bands 3 or bands 2. In Figures 1, 2 and 3 10 I have shown reinforcements 15, placed crossways, applied in seats 9.

Whenever it becomes necessary to strengthen my angular wedgeshaped pairs of bands 2, I do so by adding sections of pairs of bands together, as shown in Fig. 6, which is an enlarged cut taken at *c-c* on Fig. 1. I place pins 17, between bands 2, to hold said bands apart, to allow concrete 10 to readily flow between the sides of said sections of pairs of bands 2. The same strengthening method can be applied to the pairs of bands 3. Bolts 6 interlock said sections of said pairs of bands 2, besides anchoring the same to concrete 10. At 12 I 20 have shown the pairs of bands lengthened by letting flanges 4 overlap each other, with bolt 6 placed between the overlapping ends. By so doing I obtain a leverage between bolt 6 and flange 4, which will hold the lengthened sections of bands 2 in line. At the 30 other places, on Fig. 1, I have shown the sections of the pairs of bands 2 added together by placing their ends side by side.

Fig. 2 is a cross section of Fig. 1 at *a-a*, after concrete 10 is poured and after forms 1 are removed.

I have stated that the individual bands 2, and the individual bands 3, are placed at a suitable distance apart, so that there is an opening 11 at the top edges of the pairs of bands 2 and 3. This is done to allow concrete 10, when poured, to run through 11 and form the concrete filling 16, inside of the said pairs of bands 2 and 3. This concrete filling 16, together with bands 2 and 3, form the main angular wedgeshaped supports 2, and the lateral angular wedgeshaped supports 3, and, which, in turn, form the rectangular angular wedgeshaped seats 9.

Beam 8 is strengthened by placing pairs of bands 2 lengthways, in the lower part of beam 8, and said bands 2 are anchored to the columns (not shown) which support beam 8. As shown at 12 the sections of the 55 pairs of bands 2 rest on beam 8 and are interlocked, and anchored, in concrete 10 by means of bolts 6. At 13 the pairs of bands 2 are shown supported by walls 7 and interlocked, and anchored, in concrete 10 by 60 means of bolts 6. Fig. 3 is a longitudinal 65

section of Fig. 1 at *b-b*, after concrete 10 is poured and the form 1 removed.

Fig. 4 illustrates the fragment of an enlarged cross section of bands 2, or bands 3, as they appear after concrete 10 is poured, 76 showing concrete filling 16, as well as concrete 10 wedged upon the outside sloping surface of bands 2 and 3. Flanges 4 hold concrete filling 16 in place inside of bands 2 and 3. 78

Fig. 5 illustrates an enlarged cross section of the main pairs of bands 2, with a fragmental sideview of the sloping ends, of the lateral pairs of bands 3, resting on the sloping side of band 2. 80

The pressure, from the floors, on the sloping sides of the pairs of bands 2, and on the sloping sides of the pairs of bands 3, cannot displace said pairs of bands, because the pressure from the floor on the 85 one side of said bands counteracts the pressure on the other side. In other words the weight on the floor holds said pairs of bands in place.

The tension, which is caused by the weight 90 of the floors, is taken up by the pairs of bands 2. The floor is prevented from buckling, between the main pairs of bands 2, by lateral pairs of bands 3, and the tension in concrete 10, between the lateral pairs of 95 bands 3, is, in turn, taken up by means of reinforcements 15, as above described.

By placing the reinforcement bands on their edges I stiffen the reinforcements and thereby greatly increase their usefulness. 100 The large surface area, of the bands, as compared with round or square rods, will, further, give the fireproof materials greater contact surface with the steel, and thereby lessen the tendency for the fireproof material to slip on the steel. The simplicity of the structure is a great saving in the cost of erection of the building. Other modifications may be made without departing from the spirit of my invention. 105

I claim:—

1. In reinforcements embedded in the infilling of fireproof floors, main pairs of vertically extending spaced bands in combination with lateral pairs of vertically extending spaced bands intermediate said main pairs of bands, said pairs of bands extending from the bottom of said floor, the individual bands of said pairs of bands sloping towards each other, openings between the 115 edges of said pairs of bands accessible for said infilling, and means to attach said main bands to the supports of said floors, whereby the rectangularly shaped sloping sides of said pairs of bands form individual preferably reinforced wedgeshaped slabs when said infilling is poured. 120

2. In reinforcements embedded in the infilling of fireproof floors, main pairs of vertically extending spaced bands in combina- 125

tion with lateral pairs of vertically extending spaced bands intermediate said main pairs of bands, said pairs of bands extending from the bottom of said floors, the individual bands of said pairs of bands sloping towards each other, openings between the edges of said pairs of bands accessible for said infilling, horizontal flanges attached to the base edges of said bands, sloping ends

of said lateral bands adapted to rest against the sloping sides of said main bands, and means to attach said main pairs of bands to the supports of said floors, whereby the rectangularly shaped sloping sides of said pairs of bands form individual preferably reinforced slabs when said infilling is poured. 10

HENRY SORENSEN.
